UNITED STATES PATENT OFFICE.

JAMES F. PARKER AND CRISPIN D. ARNN, OF RALSTON, TENNESSEE.

AUTOMATIC WAGON-BRAKE.

SPECIFICATION forming part of Letters Patent No. 276,067, dated April 17, 1883.

Application filed February 13, 1883. (No model.)

To all whom it may concern:

Be it known that we, JAMES F. PARKER and CRISPIN D. ARNN, citizens of the United States, residing at Ralston, in the county of Weakley and State of Tennessee, have invented 5 certain new and useful Improvements in Automatic Wagon-Brakes; and we do hereby declare that the following is a full, clear, and exact description of the same, reference being had 10 to the annexed drawings, making a part of this specification, and to the letters and figures of reference marked thereon.

Figure 1 of the drawings is a perspective view of the front portion of a wagon-gear with 15 our improved brake attached. Fig. 2 is an under plan view of the same, and Fig. 3 a detail view in perspective of a portion of the brake mechanism and wagon-tongue.

The present invention has relation to certain 20 new and useful improvements in automatic wagon-brakes, and refers more particularly to that class in which the brake-shoes are connected to the ends of a horizontal cross-piece or bar, which has secured to it, near each 25 end, rods extending forward and over the axle, the ends being pivoted to links or short rods at right angles therewith, which in turn are pivoted to the inner end of the wagon-tongue, so that the sliding motion of the tongue 30 will operate the brakes, the tongue having an elongated slot to admit of said motion.

The object of the invention is to improve the construction of the above-mentioned class 35 of wagon-brakes, whereby simple, practical, and effective means are provided for making the connection between the hereinbefore-mentioned links or short rods and the rear end of the wagon-tongue, thus rendering the brakes more certain in their action and at the same 40 time making provision for the free vertical movement of the tongue. These objects we attain by the construction substantially as shown in the drawings, and hereinafter described and claimed.

In the accompanying drawings, A represents 45 the usual hounds of a wagon, to which is secured the bolster B, the rear ends of said hounds having connected thereto the cross-brace C, and near the forward ends or middle 50 thereof the usual axle, D, upon which are mounted the wheels E in the ordinary manner. The points of juncture between the cross-brace

C and hounds A are strengthened and re-enforced by the metal yokes F, the ends thereof being fastened upon the upper and under sides 55 of both the brace and hounds, thus forming a strong and durable connection between them. The yokes F extend out some distance beyond the brace C to form guides for the brake-beam G, through which it passes, said beam having 60 the usual brake-shoes, a, connected thereto.

To the beam G are secured one end of rods b, the forward or opposite ends extending over the axle D, and have pivotally connected to them the outer ends of arms c. These arms c, 65 near their outer ends, are pivoted to the under side of the hounds A, and at their inner extremities are pivoted to a strap, H, said strap being curved, as shown in Fig. 3, to give it additional strength. The curved strap H, at its 70 outer end, is formed with an eye, d, to connect it to the hooked end of a plate, I, said plate being adjustably connected to the under side of the wagon-tongue K, held between the hounds by a bolt, e, passing through the hounds 75 and through an elongated slot, h, in the tongue. The elongated slot h admits of the tongue K having the necessary degree of horizontal motion to bring the brake-shoes in the usual manner against the rim of the wheels. 80

If desired, a pin, f, may be employed, and when inserted in the hole g in front of the bolt e the tongue K will be prevented from moving, and thus the brakes from acting.

The important feature of our invention is 85 the manner of connecting the arms c to the tongue K by the intermediate eye-strap, H, and the hooked plate I.

It will be seen that a hinged or swiveled connection is obtained by the eye d and hook 90 upon the end of the plate I, the two being fastened together, as shown, thus allowing the tongue to have a vertical motion upon the arc of a circle, and thereby giving greater ease to the horses than where the arms are pivoted 95 directly to the tongue.

When it is desired to give the arms c a greater or less play the plate I can be adjusted upon the tongue, and set nearer to or farther away from the inner end thereof, the elongated 100 slot h being of sufficient length to admit of this adjustment or variation in the horizontal movement of the tongue.

The yokes F not only provide means for

strengthening the joint or point of connection between the hounds and cross-brace, but form guides for the brake-beam G, and also hold and support it, and thus prevent any undue strain 5 on the rods b or other portions of the brake.

Having now fully described our invention, what we claim as new, and desire to secure by Letters Patent, is—

In an automatic wagon-brake, the combination, with the transverse arms c, pivoted to the hounds A, and suitably connected to the brake-shoes by rods b, of the means, substantially as shown, of connecting the pivoted arms to the sliding and pivoted tongue K, which consist 15 of the intermediate strap, H, to which the

arms are pivoted, and the plate I, said strap and plate having, respectively, an eye and hook for making a hinged connection at the point of attachment, whereby the tongue is enabled to work on its pivotal bearing without operating the brake-shoes, substantially as and for the purpose set forth. 20

In testimony that we claim the above we have hereunto subscribed our names in the presence of two witnesses.

JAMES F. PARKER.
CRISPIN D. ARNN.
